UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING APPARATUS

Application filed April 27, 1928. Serial No. 273,295.

This invention relates to mining apparatus and more particularly, but not exclusively, pertains to an adjustable skid mounting for a coal mining machine.

5 An object of this invention is to provide an improved mining apparatus. Another object is to provide an improved adjustable skid mounting for a coal mining machine. A further object is to provide an adjustable skid 10 mounting for a mining machine whereby the elevation and angle of the machine may be varied. Still another object is to provide an improved adjustable skid mounting for a mining machine whereby the latter may be 15 tilted or rocked about longitudinal and transverse axes. Yet another object is to provide an improved adjustable skid mounting slidable on its bottom on the mine bottom and having provision for receiving and supporting a self-contained coal mining machine of the kerf cutting type and including means for varying the angle and elevation of the machine to suit different operating conditions. These and other objects of this invention will, however, hereinafter more fully appear.

In the accompanying drawings there is shown for purposes of illustration one embodiment which the invention may assume in practice.

30 In these drawings,—

Fig. 1 is a side elevation of the improved mining apparatus.

Fig. 2 is a plan view of the apparatus shown in Fig. 1.

35 Fig. 3 is an end elevational view of the apparatus shown in Figs. 1 and 2.

Fig. 4 is a detail sectional view taken on line 4—4 of Figs. 2 and 3.

Fig. 5 is a detail sectional view taken on 40 line 5—5 of Figs. 1 and 4.

Fig. 6 is a detail sectional view taken on line 6—6 of Fig. 4.

Fig. 7 is a somewhat diagrammatic view 45 illustrating the machine supported in its elevated position, the machine being shown tilted as indicated in dotted lines.

In this illustrative embodiment of the invention there is shown an adjustable skid mounting 1 comprising a horizontal widely 50 extended bottom engaging plate 2 having a

flat bottom engaging surface 3 and upturned or curved sides 4 and ends 5 to permit free universal movement of the skid over the mine bottom. Adjustably mounted on the skid and supported by improved elevating and tilting mechanism generally designated 6 is a machine receiving and supporting frame 7 consisting of a transverse horizontal plate 8 secured at its ends as by riveting to transverse angle members 9 which are in turn rigidly secured at their ends to parallel side angle members 10. As shown these side angle members 10 are rigidly connected at their rear ends to a casing 11 housing suitable electrical controlling apparatus (not shown).

The improved elevating and tilting mechanism comprises depending bearing brackets 15 rigidly secured to the side angle members 10 at each side of the skid mounting and journaled in these brackets are rear and front transverse horizontal shafts 16 and 17, respectively. Rigidly fixed to these shafts are supporting arms 18 and 19 respectively, and these arms constitute the sole supporting means for the machine on the skid. The lower ends of the front supporting arms 19 are pivotally connected at 20 to a bearing block 21 bolted to the bottom plate of the skid 2 at the sides of the latter. It will also be noted that the lower ends of the rear arms 18 are pivotally connected at 22 to sliding blocks 23 slidably mounted in longitudinal guideways 24 at each side of the rearward end of the skid. As illustrated, the supporting arms 18 and 19 at one side of the skid mounting have 35 formed integral therewith upstanding arms 25 and 26 respectively and the outer ends of these latter arms are bifurcated and pivotally connected at 27 and 28 respectively to one of the ends of a pair of link members or arms 30. The other ends of these link members or arms 30 are pivotally connected at 31 to non-rotatable trunnion blocks 32 and 33. These trunnions are herein in the form of nuts having internal threads engaging the right and left hand threads on a rotatable and axially movable adjusting screw 34. This screw extends longitudinally of the apparatus at one side thereof as clearly shown in Figs. 1 to 3 and is mounted for rotative and

axial movements intermediate its ends in an upstanding bracket or bearing member 35 rigidly secured to the adjacent side angle member 10. In this instance the front end of the screw 34, as clearly shown in Fig. 4, extends axially into a hollow rotatable shaft or sleeve 36 suitably rotatably mounted within bearings 37 carried within a casing 38 suitably rigidly fixed to the adjacent side angle member 10. Herein threadedly connected at 39 within the front end of the rotatable sleeve 36 is a pressure screw 40 having its rearward end abutting the front end of the adjusting screw 34 as at 41. It will also be noted that the adjusting screw 34 is splined at 42 to the rotatable sleeve 36, the screw having axial sliding movement relative to the sleeve but being at all times rotatable with the sleeve. Also keyed at 43 to the rotatable sleeve 36 is a locking member 44 having formed on its outer periphery suitable locking teeth 45 (see also Fig. 5). Cooperating with this locking member 44 is a toothed locking member 46 keyed at 47 to a horizontal longitudinally extending rock shaft 48 suitably rotatably mounted within the casing 38. This rock shaft 48 has fixed thereto at its outer end an operating handle 49. It will thus be evident that when the locking member 46 is in the released position as indicated in full lines in Fig. 5 the sleeve 36 together with the adjusting screw 34 are free to rotate and when the locking member is swung laterally in one direction or another, for instance to the dotted line position shown in Fig. 5, one of its teeth engages the locking teeth on the locking member 46, and as a result the sleeve 36 and screw are held against rotation, it then being possible to move the adjusting screw axially as will later be described. The devices for manually rotating the sleeve 36 and the adjusting screw 34 are generally designated 50 and 51 respectively, and as these devices are substantially the same in construction a description of one will suffice for both. As shown in Figs. 4 and 6, the rotating device 51 comprises an operating handle or lever 52 pivotally connected at 53 to the element rotated thereby and held in position by suitable thrust washers 54 carried by the said element, these washers engaging the sides of the lever. Fixed to a rock shaft 55 rotatably mounted on the lever 52 is a reversible pawl 56 adapted to cooperate with ratchet teeth 57 formed on the element to be rotated. Secured to this rock shaft 55 is an operating lever 58 by means of which the position of the pawl 56 may be reversed thereby permitting the pressure screw 40 to be rotated in opposite directions. The pawl 56 is held in its different adjusted positions by means of a spring pressed plunger 59 carried by the lever 52. From the foregoing it will be seen that when the rotating device 50 is actuated the sleeve 36 and adjusting screw 34 may be rotated, it being

assumed that the locking member 46 is released. When the other rotating device 51 is actuated and the sleeve 36 is held against rotation the screw 34 may be adjusted axially.

Means is provided whereby the machine may be slightly tilted about a longitudinal axis relative to the frame 7 and to this end suitable bearing brackets 65 are provided rigidly secured to the bottom sides of the transverse members 9 at the front and rear ends of the plate 8. Supported within these brackets 65 are horizontal shafts 66 disposed beneath and extending longitudinally of the machine in the central longitudinal vertical plane thereof. Pivotaly mounted on these shafts 66 are brackets or supports 67 rigidly secured to the bottom of a self-contained coal mining machine generally designated as an entirety by the reference characters 68, this machine being detachably secured to the supports 67 and adapted to be dismounted from the skid and operated on the mine bottom in the usual manner. As shown, secured to the bottom of the transverse plate 8 at each side thereof are brackets 69 having threadedly connected thereto adjustable set screws 70, engaging the bottom of the machine at the front end of the latter, these set screws being disposed at the sides of the longitudinal axis about which the machine is adapted to be tilted or rocked. It will further be noted that there is a substantial space or clearance between the bottom of the machine and the plate 8 to permit the desired rocking movement of the machine about its longitudinal axis.

The coal mining machine 68 is herein of the flexibly fed, continuous cutter, longwall type and herein is of the same general construction as that described in my copending application Serial No. 136,446, filed September 20, 1926. This machine generally comprises a casing or body 71 housing a driving motor and is provided with flexible feeding means including a feed sprocket 72 rotatable about a vertical axis at one end of the machine and cooperating with a flexible feed chain 73. Suitable guide sheaves or rolls 74 are provided on the machine at each side of the feed sprocket 72 and are so arranged as to permit reeving of the feed chain relative to the feed sprocket in various manners as clearly described in my copending application mentioned above. Also driven by the machine motor is cutting mechanism including an elongated cutter chain carrying cutter bar 75 pivotally mounted on a vertical axis at the end of the machine remote from the feed sprocket and swingable laterally to positions at either side of the machine and lengthwise of the machine. Suitable means is employed to rigidly lock the cutter bar in its different adjusted positions and comprising a rotatable locking pin 76 carried by the cutter bar and engageable with appropriately located

notches on the machine casing. The feed chain is adapted to be suitably connected to the locking pin 76 and upon rotation of the feed sprocket 72 the feed chain is drawn in and the bar swung by power. The connection for the feed chain to the bar locking pin and the bar locking means are both clearly described in my copending application mentioned above and therefore further description is herein submitted to be unnecessary.

In the use of the improved mining apparatus it will be assumed that the same is positioned at the coal face and the cutter bar is in the full line position as shown in Fig. 2. In case the mine bottom is uneven the operator may adjust the set screws 70 and thereby tilt the machine 68 about the pivots 66 until the cutter bar assumes a position in a substantially horizontal plane. The operator then connects the feed chain 73 to the cutter bar locking pin 76 as indicated in full lines in Fig. 2 and upon rotation of the feed sprocket 72 the feed chain is drawn in and the cutter bar swung about its pivot, from the full line position shown in Fig. 2 to the dotted line position to effect a sumping cut. The cutter bar is thereafter rigidly locked in position at a right angle to the machine body by the locking means 76. The feed chain 73 is then disconnected from the cutter bar locking means and extended from the feed sprocket 72 around certain of the guide sheaves 74 forwardly longitudinally of the machine to a suitable roof jack disposed adjacent the coal face in advance of the apparatus. The feed sprocket is then again rotated by power and the machine fed bodily relative to the feed chain along the coal face to effect a longwall cutting operation. If it is desired to change the elevation of the machine, that is, to adjust the machine from the position shown in Fig. 1 to the position shown in Fig. 7 or in any intermediate position so that the cutter bar may operate in different planes, the operator grasps the lever 49 and swings the locking member 46 to the full line position shown in Fig. 5 thereby releasing the locking member 44. The operator then grasps the operating handle of the ratchet and pawl device 50 and oscillates the same thereby rotating the sleeve 36 together with the adjusting screw 34 splined thereto. Rotation of this screw 34 causes the trunnion nuts 32, 33 to move axially along the adjusting screw and relative to each other, thereby effecting swinging movement of the supporting arms 18 and 19 in opposite directions about their pivots and thereby causing the machine to be raised or lowered as desired. It is evident that the screw 34 may be rotated in the opposite direction upon reversal of the position of the pawl 56. If it is desired to vary the angle of the machine, that is, to tilt the machine about a substantially transverse axis, the operator swings

the locking member 46 into the dotted line position shown in Fig. 5 thereby locking the sleeve 36 against rotation. The operator then grasps the handle of the ratchet and pawl device 51 and moves the same back and forth, thereby effecting rotation of the pressure screw 40 relative to the then stationary sleeve 36 and as the screw 40 abuts the rear end of the adjusting screw 34 the latter is slid axially relative to the sleeve 36 thereby effecting swinging of the arms relative to each other, the slidable blocks 23 moving within their guideways 24 at that time and as a result causing the machine to be moved into a position opposite to that indicated by dotted lines in Fig. 7. It is obvious that if the adjusting screw 34 is permitted to move axially in the opposite direction the machine may be tilted in the opposite direction to a position similar to that indicated by dotted lines in Fig. 7. Other uses and advantages of the improved adjustable skid mounting will be clearly apparent to those skilled in this art.

While I have in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining apparatus, a body carrying cutting mechanism, a skid, and adjustable supporting means between said body and skid including pivoted supporting arms, one of said arms being pivoted to said skid while the other has a sliding connection with said skid, and means adjustably connected to both arms for swinging said arms about their pivots to vary the position of said body relative to said skid. 100
2. In a mining apparatus, a body carrying cutting mechanism, a skid, and adjustable supporting means between said body and skid including pivoted supporting arms, certain of said arms being pivoted to said skid while the others have a sliding connection with said skid, and means for effecting relative swinging movement of said arms to tilt said body relative to said skid, said arms having sliding connection with said skid and moving within their slides during such tilting movement. 110
3. In a mining apparatus, a body carrying cutting mechanism, a skid, and adjustable supporting means between said body and skid including pivoted front and rear supporting arms, and means adjustably connected to both arms at the opposite sides of their pivots from said skid for simultaneously swinging said arms to vary the elevation of said body relative to said skid. 120
4. In a mining apparatus, a body having 130

- cutting mechanism, and a support for said body, a skid, and adjustable supporting means between said body and support and said skid including arms pivoted on said support, certain of said arms being pivotally connected to said skid, and means including a mechanical connection between and adjustably connected with said arms at the opposite sides of their pivots from said skid for swinging said arms about their pivots to vary the elevation of said body relative to said skid. 70
5. In a mining apparatus, a body having cutting mechanism, and a support for said body, a skid, and adjustable supporting means between said body and support and said skid including arms pivoted on said support, certain of said arms being pivotally connected to said skid, and a sliding connection between said other arm and said skid, 75 and means including a mechanical connection between and adjustably connected with said arms for swinging said arms about their pivots to vary the elevation of said body relative to said skid. 80
6. In a mining apparatus, a body carrying cutting mechanism, a skid, and adjustable supporting means between said body and skid including pivoted supporting arms certain of which are pivotally connected to said skid, 85 and means for swinging said arms about their pivots to vary the elevation and angle of said body relative to said skid. 90
7. In a mining apparatus, a body carrying cutting mechanism, a skid, and adjustable supporting means between said body and skid including pivoted supporting arms certain of which are pivotally connected to said skid while the other arms have a sliding connection with the latter, and means for swinging said arms about their pivots to vary the elevation and angle of said body relative to said skid. 95
8. In a mining apparatus, a body carrying cutting mechanism, a skid slidable on its bottom on the mine bottom, and adjustable supporting means between said body and skid comprising pivoted front and rear supporting arms, and means for swinging said arms about their pivots comprising a screw, nuts 100 cooperating with said screw, means connecting said nuts and arms and engaging the latter at the opposite sides of their pivots from said skid. 105
9. In a mining apparatus, a body carrying cutting mechanism, a skid slidable on its bottom on the mine bottom, and adjustable supporting means between said body and skid comprising pivoted supporting arms, and means for swinging said arms about their pivots comprising a screw having reversely threaded portions, reversely threaded nuts 110 cooperating with said threaded portions, angularly movable links pivotally connected to said nuts and arms and forming a connection therebetween, and means for rotating said arms including a manually operable ratchet and pawl device. 115
- said screw to effect axial movement of said nuts relative thereto. 120
10. In a mining apparatus, a body carrying cutting mechanism, a skid, and adjustable supporting means between said body and skid comprising pivoted supporting arms, and means for swinging said arms about their pivots comprising a screw having reversely threaded portions, reversely threaded nuts cooperating with said threaded portions, links connecting said nuts and arms, and means for moving said screw axially. 125
11. In a mining apparatus, a body carrying cutting mechanism, a skid, and adjustable supporting means between said body and skid comprising pivoted supporting arms, and means for swinging said arms about their pivots comprising a screw having reversely threaded portions, reversely threaded nuts cooperating with said threaded portions, links connecting said nuts and arms, means for rotating said screw, and means for moving said screw axially. 130
12. In a mining apparatus, a body carrying cutting mechanism, a skid, and adjustable supporting means between said body and skid comprising pivoted supporting arms, and means for swinging said arms comprising an axially movable screw having threaded portions, nuts engaging the threaded portions of said screw, links connecting said nuts and arms, and means for moving said screw axially. 135
13. In a mining apparatus, a body carrying cutting mechanism, a skid slidable on its bottom on the mine bottom, and adjustable supporting means between said body and skid comprising pivoted supporting arms, means for swinging said arms comprising a rotatable screw, oppositely movable nuts 140 threadedly connected to said screw, links pivotally connected to said nuts and arms and forming a connection therebetween, and means for rotating said screw to effect axial movement of said nuts relative thereto. 145
14. In a mining apparatus, a body carrying cutting mechanism, a skid, and adjustable supporting means between said body and skid comprising pivoted arms, means for moving said arms comprising an axially movable screw, oppositely movable nuts 150 threadedly engaging said screw, links connecting said nuts and arms, and means for moving said screw axially. 155
15. In a mining apparatus, a body carrying cutting mechanism, a skid, and adjustable supporting means between said body and skid comprising pivoted supporting arms, means for swinging said arms comprising a rotatable screw, oppositely movable nuts 160 threadedly connected to said screw, links pivotally connected to said nuts and arms and forming a connection therebetween, and means for rotating said screw including a manually operable ratchet and pawl device. 165

16. In a mining apparatus, a body having cutting mechanism, a skid, and adjustable supporting means between said body and skid comprising pivoted arms, means for swinging said arms comprising an axially movable screw, nuts threadedly engaging said screw, links connecting said nuts and arms, and means for moving said screw axially including a pressure screw arranged coaxially with and engaging said first mentioned screw.
17. In a mining apparatus, a body carrying cutting mechanism, a skid, and adjustable supporting means between said body and skid comprising pivoted arms, means for swinging said arms comprising a screw, oppositely movable nuts threadedly connected to said screw, connections between said nuts and arms, means for rotating said screw to effect opposite movement of said nuts, and means for moving said screw axially to effect simultaneous movement of said nuts in the same direction.
18. In a mining apparatus, a self-contained mining machine, a frame supporting said machine, means carried by said frame for tilting said machine about a longitudinal axis, a skid, and means between said frame and skid for bodily elevating said machine.
19. In a mining apparatus, a self-contained mining machine, a frame supporting said machine, means carried by said frame for adjusting said machine about a longitudinal axis, a skid, and adjustable supporting means between said frame and skid comprising pivoted supporting arms, and means for swinging said arms about their pivots to vary the elevation of said mining machine relative to said skid.
20. In a mining apparatus, a self-contained mining machine, a frame supporting said machine, means carried by said frame for adjusting said machine about a longitudinal axis, a skid slidable on its bottom on the mine bottom, and adjustable supporting means between said frame and skid comprising pivoted supporting arms, and means for swinging said arms about their pivots to vary the elevation of said mining machine relative to said skid comprising a screw, oppositely movable nuts threadedly connected to said screw, links connecting said nuts and arms, and means for rotating said screw to effect axial movement of said nuts relative thereto.
21. In a mining apparatus, a skid, cutting mechanism, and adjustable supporting means between said skid and cutting mechanism comprising relatively adjustable front and rear supports, and mechanism including a mechanical connection between said supports for simultaneously adjusting said supports to vary the elevation of said cutting mechanism or for relatively adjusting said supports to effect tilting of said cutting mechanism relative to said skid.
22. In a mining apparatus, a portable support movable upon the mine bottom, a self-contained mining machine of the type adapted to normally operate on its own bottom on the mine bottom and including cutting mechanism and flexible feeding means including a flexible feeding element, and adjustable supporting means between said support and mining machine including relatively adjustable front and rear supports, and mechanism for simultaneously adjusting said second mentioned supports to vary the elevation of said mining machine or for relatively adjusting said supports to effect tilting of said mining machine relative to said first mentioned support, said flexible feeding means being operative to propel the apparatus bodily over the mine bottom during the cutting operation.
23. In a mining apparatus, a skid slidable on its bottom on the mine bottom, cutting mechanism, and adjustable supporting means between said skid and said cutting mechanism including front and rear supporting arms pivoted between their ends, and mechanism including a mechanical connection between said arms at one side of their pivots for adjusting all of said arms simultaneously to vary the elevation of said cutting mechanism or for relatively adjusting said arms to effect tilting of said cutting mechanism relative to said skid.
24. In a mining apparatus, a portable support, cutting mechanism, and adjustable supporting means between said support and said cutting mechanism including supporting arms pivoted between their ends, one of said arms having a sliding connection with said support, and mechanism including a mechanical connection between said arms at one side of their pivots for adjusting said arms simultaneously to vary the elevation of said cutting mechanism or for relatively adjusting said arms to effect tilting of said cutting mechanism relative to said support.
25. In a mining apparatus, a skid slidable on its bottom on the mine bottom, cutting mechanism, and adjustable supporting means between said skid and said cutting mechanism including pivoted front and rear supporting arms constituting the sole support between said cutting mechanism and said skid, and mechanism including a single mechanical connection extending between and adjustably connected to all of said arms at the other sides of their pivots from said skid for swinging said arms to vary the elevation of said cutting mechanism relative to said skid.
26. In a mining apparatus, a skid slidable on its bottom on the mine bottom, cutting mechanism, and adjustable supporting means between said skid and said cutting mechanism including pivoted front and rear sup-

- porting arms constituting the sole support between said cutting mechanism and said skid, one of said arms having a pivotal connection with said skid while the other has a sliding connection with said skid, and mechanism including a mechanical connection extending between and adjustably connected to said arms for swinging the latter to vary the elevation of said cutting mechanism.
27. In a mining apparatus, a portable support, cutting mechanism, and adjustable supporting means between said support and said cutting mechanism including relatively adjustable front and rear supports, one of said supports having a sliding connection with said portable support, and mechanism including a mechanical connection between and adjustably connected with said front and rear supports for simultaneously or relatively adjusting said supports to change the elevation of and tilt said cutting mechanism.
28. In a mining apparatus, a skid slideable on its bottom on the mine bottom, cutting mechanism, and adjustable supporting means between said skid and said cutting mechanism including pivoted front and rear arms constituting the sole support between said cutting mechanism and said skid, and mechanism for swinging said arms about their pivots to change the elevation of or tilt said cutting mechanism relative to said skid including an adjusting element extending longitudinally along one side of said cutting mechanism and connections between all of said arms and said adjusting element.
29. In a mining apparatus, a skid slideable on its bottom on the mine bottom, a self-contained mining machine of the type adapted to normally operate on its own bottom on the mine bottom and including cutting mechanism and flexible feeding means including a flexible feeding element, and adjustable supporting means between said skid and said machine including relatively adjustable front and rear supports, and mechanism operatively connected to said supports for adjusting the latter to move bodily said machine into parallel planes to vary the elevation of said machine relative to said skid or for tilting said machine about a transverse horizontal axis relative to said skid, said feeding means being operative to propel the apparatus bodily over the mine bottom during the cutting operation.
30. In a mining apparatus, a portable support movable upon the mine bottom, a self-contained mining machine of the type normally slideable on its own bottom on the mine bottom during cutting and including cutting mechanism and feeding mechanism, and adjustable supporting means between said support and machine including means for bodily adjusting said support into parallel horizontal planes for varying the elevation of the machine relative to said support and for tilt-
- ting said machine relative to said support, said feeding means being operative to propel the apparatus bodily over the mine bottom during the cutting operation.
31. In a mining apparatus, a portable support movable upon the mine bottom, a self-contained mining machine of the type adapted to normally operate on its own bottom on the mine bottom and including flexible feeding means having a flexible feeding element, and adjustable supporting means between said support and machine including means for tilting said machine about a longitudinal axis, for varying the elevation of said machine relative to said support, and for tilting said machine about a transverse axis relative to said support, said flexible feeding means being operative to propel the apparatus bodily over the mine bottom during the cutting operation.
32. In a mining apparatus, a skid slideable on its bottom on the mine bottom, cutting mechanism, and adjustable supporting means between said skid and said cutting mechanism including means for tilting said cutting mechanism about a longitudinal axis relative to said skid, for varying the elevation of said cutting mechanism, and for tilting said cutting mechanism about a transverse axis relative to said skid, said means for tilting said cutting mechanism about a longitudinal axis being separate and distinct from said elevating and tilting means.
33. In a mining apparatus, a bottom skid, a frame, cutting mechanism carried by said frame, and mechanism between said skid and frame for varying the elevation of said frame and cutting mechanism comprising supporting means having pivoted front and rear arms, and mechanism including a mechanical connection between said front and rear arms and connected to the latter at the opposite sides of their pivots from said skid for effecting simultaneous swinging movement of said arms, the connection between said arms and said mechanical connection lying in a common vertical longitudinally extending plane.
34. In a mining apparatus, a bottom skid, a frame, cutting mechanism carried by said frame, and vertically adjustable supporting means therefor comprising spaced front and rear arms pivoted between their ends and connected to said skid at one side of their pivots, aligned rotatable screw means mounted on said frame and operatively connected to and extending between said front and rear arms at the other side of their pivots, and means for actuating said screw means.
35. In a mining apparatus, a frame, a cutting mechanism carried by said frame and mechanism for varying the elevation of said frame comprising a sliding bottom skid having pivoted front and rear arms disposed at opposite sides of the apparatus, and mecha-

5 nism including a mechanical connection common to the swinging of all of said arms and extending between said arms at one side of said frame for effecting simultaneous swinging movement of said arms to elevate said frame.

10 36. In a mining apparatus, a bottom skid, a frame, cutting mechanism carried by said frame, and adjustable supporting means between said frame and skid for varying the elevation of said frame comprising spaced front and rear arms pivoted between their ends at opposite sides of said frame and connected to said skid at one side of their 15 pivots, adjusting means mounted on said frame for effecting swinging movement of said arms including a mechanical connection extending between said arms at one side of said frame and movably connected to said arms at the other side of their pivots, and means for actuating said adjusting means to effect simultaneous swinging movement of all of said arms.

20 37. In a mining apparatus, a bottom skid, kerf cutting mechanism, and adjustable supporting means between said skid and kerf cutting mechanism including an adjustable front support and an adjustable rear support, one of said supports being pivotally connected to said skid while the other has a sliding connection with said skid, and means for simultaneously adjusting said supports to vary the elevation of said kerf cutting mechanism.

25 38. In a mining apparatus, a bottom skid, kerf cutting mechanism, and adjustable supporting means between said skid and kerf cutting mechanism including an adjustable front support and an adjustable rear support, one of said supports being pivotally connected to said skid while the other has a sliding connection with said skid, and means for simultaneously adjusting said supports to vary the elevation of said kerf cutting mechanism and for relatively adjusting said supports to effect tilting of said kerf cutting mechanism relative to the horizontal.

30 39. In a mining apparatus, kerf cutting mechanism including a pivoted kerf cutter, a skid adapted to rest upon and slide in any direction over the mine bottom, and adjustable supporting means between said cutting mechanisms and said skid including pivoted front and rear supporting arms and means adjustably connected to both arms for simultaneously swinging said arms to vary the elevation of said cutting mechanism relative to said skid or for relatively adjusting said arms to change the angle in altitude of said cutting mechanism.

35 40. In a mining apparatus, kerf cutting mechanism including a pivoted kerf cutter, a skid adapted to rest upon and slide in any direction over the mine bottom, and adjustable supporting means between said cutting mechanism and said skid including pivoted

45 arms, certain of said arms being pivotally connected to said skid, and means including a mechanical connection between and adjustably connected with said arms for swinging said arms about their pivots to vary the elevation of said cutting mechanism or for relatively adjusting said arms to change the angle in altitude of said cutting mechanism. 70

50 41. In a mining apparatus, kerf cutting mechanism including a pivoted kerf cutter, a skid adapted to rest upon and slide in any direction over the mine bottom, and adjustable supporting means between said cutting mechanism and said skid comprising pivoted front and rear supporting arms, and means for swinging said arms simultaneously about their pivots to vary the elevation of said cutting mechanism or for relatively adjusting said arms to change the angle in altitude of said cutting mechanism, said means comprising a screw, nuts threadedly connected to said screw, means connecting said nuts and arms, and means for actuating said screw. 80

55 42. In a mining apparatus, kerf cutting mechanism including a pivoted kerf cutter, a skid adapted to rest upon and slide in any direction over the mine bottom, and adjustable supporting means between said cutting mechanism and skid including an adjustable front support and a relatively adjustable rear support, and means including a mechanical connection between and adjustably connected with said supports for simultaneously adjusting said supports to vary the elevation of said cutting mechanism or for relatively adjusting said supports to change the angle in altitude of said cutting mechanism. 90

60 In testimony whereof I affix my signature.
